ROTARY PRINTING PRESS

George Hantopoulos, New York, N. Y.

Application July 29, 1938, Serial No. 221,916

6 Claims. (Cl. 101—219)

This invention relates to improvements in the running condition of rotary printing presses.

In the past a great deal of the press running time has been lost and a great amount of paper wasted by breaking in the process of continuously feeding paper from the roll through the impression cylinders to the folder. Considerable damage has also been done in rotary printing presses by what is commonly called "chucks" of the folder, or invisible causes, breaking the pins of the folder.

My experiments prove that, the press, in action, practically ignores every resistance, between tension and the pins of the folder.

Therefore, the whole load in a press, from tension is carried by the pins of the folder; therefore, the load was the invisible cause of breaking the pins, and damaging the press.

To eliminate the above stated wasted paper, and damaging of the press, I invented differential circumference between inside and outside in either or both of impression and plates of cylinders, (larger inside, and smaller outside), to increase the strength of the paper, and remove pulling force from the edges of same.

And also a differential circumference between first pair of impression cylinders, and second pair of impression cylinders, to control sheets and reduce tension, and by reducing tension, I reduce the load on the pins of the folder.

The invention is a printing press of the rotary type having printing plate cylinders, with the circumference of the central portion of said cylinders slightly larger than that of the ends of the cylinders, and with the second cylinder slightly larger than the first cylinder of a unit.

Considerable trouble is continually experienced in rotary presses, and, particularly, presses of the newspaper type, because of breakage of the paper which causes waste, and this is caused by the fact that substantially the entire pull on the paper is through the pins of the folders, and this causes continuous breaking thereof. This causes a considerable loss in the running time of printing presses and an enormous waste of paper, and, furthermore, considerable time is lost through repairing broken pins.

The object of this invention is, therefore, to eliminate the cause of the breakage of the paper of rotary printing presses, and thereby increase the capacity of the press, substantially eliminate waste, and also step up the speed.

Another object is to provide means for relieving the tension at, or adjacent to, the edges

of the paper of a rotary printing press by providing means for frictionally gripping the paper throughout the central part thereof.

A further object is to provide means for readily increasing the diameter and circumference of the printing plate rollers of rotary printing presses throughout the intermediate portions thereof.

And a still further object is to provide improvements in rotary printing presses which relieve and also distribute the strain of the paper and frictionally urge the paper through the press from intermediate parts thereof which are of a simple and economical construction.

With these ends in view the invention embodies a rotary printing press in which the intermediate portions of the plate cylinder assemblage are of a slightly larger diameter than the ends, and in which the latter set of plate and impression cylinders is slightly larger than those of the other set when two sets are combined in a unit.

Other features and advantages of the invention will appear from the following description taken in connection with the drawing, wherein:

Figure 1 is a diagrammatic view showing a section through a unit of a printing press with the parts indicated by single lines.

Figure 2 is a plan view of the unit shown in Figure 1.

Figure 3 is a detail showing one of the printing plate cylinders of the press of the type shown in Figures 1 and 2.

Figure 4 is a similar view showing a cylinder of a press of an alternate design.

Figure 5 is also a similar view showing a cylinder of a press of another alternate design.

Figure 6 is a detail in which the parts are exaggerated, showing that the latter set of cylinders is larger than the other set.

In the drawing the improvements are illustrated as they may be used, wherein numeral 1 indicates a roll of paper, numeral 2, a folder, numerals 3 and 4, printing plate cylinders, and numerals 5 and 6, impression cylinders.

It will be understood that any number of units may be used in one press, and cylinders of any width may be used to accommodate presses of any width. The roll of paper, as indicated by the numeral 1, is generally located below the floor, and is fed upward through the first set of printing cylinders, however, for the purpose of illustrating this invention, the paper roll is shown mounted at the end of the machine, and the rotation thereof is retarded by friction

belts with weights in the pulleys at their lower ends, or any friction, holding or retarding means may be used. The paper, which is indicated by the numeral 7, passes upward over a roller 8, around a roller 9, and upward between the cylinders 3 and 5, and then downward around the cylinder 6 and upward between the cylinders 4 and 6.

The paper then passes upward over a roller 10 around another roller 11, another roller 12 and over a cylinder 13, from where it passes downward between pinch rollers 14 in the folder 2 where it is gripped by the usual pins 15, that provide the pulling means for drawing the paper 15 through the machine.

The cylinders may be driven in any manner, however, they are generally geared together as shown in Figure 2, with the cylinders 3 and 5 geared together by gears 16 and 17, the cylinders 20 5 and 6 geared by gears 18 and 19, and the cylinders 6 and 4 by the gears 20 and 21. All of the cylinders, therefore, rotate at a constant speed, and, therefore, in order to provide a differential between the speed of the cylinders 4 and 6 and 25 that of the cylinders 3 and 5, it is only necessary to slightly increase the diameters of the cylinders 4 and 6.

In the machine illustrated, the printing plate cylinders 3 and 4 are provided with printing plates 30 22, 23, 24 and 25 on the cylinder 3, and plates 26, 27, 28 and 29 on the cylinder 4, and these plates are formed in two halves, with the halves secured to the cylinders which are of the same diameter and generally finished absolutely smooth 35 and true. The impression cylinders 5 and 6, which are covered with blankets, are also substantially round and uniform throughout their lengths.

These plates are shown in section in Figure 3, 40 and the drawing, which is exaggerated, shows the plates 23 and 24 slightly larger than the plates 22 and 25, however, these plates may be formed and assembled on the cylinder with a gradual continual slope toward the center, providing a 45 slightly larger diameter throughout the intermediate part of the printing plate assembly than the diameter at the ends. The drawing illustrates the intermediate plates slightly thicker than the plates at the ends, however, in Figure 5, the 50 thickness of the plates, which are indicated by the numerals 30 and 31, is tapered, and it will be understood that the plates shown in Figure 3 may also be tapered in order to provide a larger diameter at the center; or any means may be used 55 for slightly increasing the diameter of the printing plates at the center or throughout the intermediate part thereof so that the diameter is slightly larger in the central portion than at the ends, so that the paper is positively drawn by 60 pulling on the center thereof instead of at the ends. It has been found by numerous experiments that with the engaging surfaces of the printing plates substantially parallel, the tension at the edges of the paper causes breaking of the 65 paper. Therefore, by shaping the rollers in this manner, and thereby reducing the tension at the edges, the tension is placed upon the body of the paper throughout the central portion thereof, and the newspaper printing presses with the plate 70 cylinders formed in this manner do not break the paper, and waste is, therefore, substantially eliminated.

Figure 4 merely illustrates an arrangement of a three plate cylinder, with a central plate 32 75 slightly larger than the end plates 33 and 34,

however, it will also be understood that the central plate 32 may be parallel to the surface of the cylinder, and the end plates 33 and 34 may be sloped or tapered slightly, or, as hereinbefore stated, these plates may be arranged in any manner in order to provide a plate cylinder assembly slightly larger at the center or throughout the intermediate portion thereof. These plates may also be formed by planing or grinding material from the back thereof, or set with shims, 10 or assembled in any manner or by any means.

Another important feature in the successful operation of newspaper printing presses has been found to be in an improved method of urging the paper through the press, as, in presses of this type, a substantial part of the load is placed upon the pins and they attempt to draw the paper through the press; and, in order to remove this load from the pins, it has been found that, by increasing the diameter of the cylinder 4, or of 20 the cylinders 4 and 6, a slight differential between the circumferential speed of the cylinders 3 and 5 and that of the cylinders 4 and 6 is accomplished, and this causes a pull particularly on the central part of the paper with cylinders 25 formed as hereinbefore described, and this has a tendency to urge the paper toward the folder, or even feed the paper through the machine. The paper is, therefore, positively gripped and fed or urged toward the folder by these last two cylinders, and this relieves the tension and also the load on the pins in the folder.

The increased diameter of the cylinder 4, or of the cylinders 4 and 6, is exaggerated in the drawing, as this is only about three thousandths of an 35 inch in the circumference, but this slight difference relieves the tension and actually draws the paper from the two former cylinders. The increased diameter of the cylinders at the center or through the intermediate portions is also very slight, the cylinders being about two or three thousandths of an inch larger at the center than at the ends.

To maintain the required differential in circumference and be the most beneficial it is essential 45 that the following method should be used in installing the plates on the cylinders of a rotary printing press.

The interior end of an interior plate should be lowered carefully upon the cylinder, then it should be slid to its position, and when the other end of the plate reaches a height of two to three inches from the cylinder, it should be let drop on the cylinder with a knock, and next it should be turned sidewise to the head register, and then turn it off or back from the head register a little. The outside plate should be lowered and placed 50 on the cylinder carefully, with the same motion, but soundless.

It will be understood that other changes may be made without departing from the spirit of the invention. One of which changes may be in the use of any other means for slightly increasing the diameter or circumference of the plate cylinders assembly or impression cylinders, another may be in the use of other means for increasing the diameter of the latter set of cylinders, and still another may be in the use of any other improvements in combination with these changes, or in the use of these changes in 70 a press or apparatus of any other type.

The construction will be readily understood from the foregoing description. In use the remainder of the press will operate in the usual manner, and the printing plates will be assem- 75

bled on their respective cylinders in their usual locations, however, the circumference at the center or throughout the intermediate portions thereof will be slightly larger than at the ends, and this increases friction at the centers of the cylinders, thereby placing the load or actually pulling the paper from the central part, and removing or relieving the tension or pulling force at the edges, and, in doing this, and also in providing the differential in the traveling or surface speed by increasing the surface speed of the last set of cylinders makes it possible to minimize breaking the sheet and wasting the paper.

Having thus fully described the invention, what I claim as new, and desire to secure by Letters Patent, is:

1. A rotary printing press of the type having printing plate cylinders in combination with impression cylinders, in which the diameter of the cylinders at the center is slightly larger than the diameter at the ends thereof.

2. A rotary press of the type having printing plate cylinders in combination with impression cylinders, in which the diameter of the said cylinders is slightly larger throughout the intermediate portions thereof than at the ends.

3. A rotary printing machine, as described in

claim 2, in which the latter cylinders of a unit are slightly larger than the former.

4. The art or process of moving paper through rotary printing presses which consists of urging said paper forward by frictionally engaging the paper by drawing means at the longitudinal center thereof with the engaging means being gradually relieved toward the edges so that the edges are substantially free.

5. The art or process of evenly distributing the tension on paper traveling through rotary printing presses, which comprises increasing gripping throughout the longitudinal center of the paper passing between the printing plate cylinders and the impression cylinders.

6. In a rotary printing press of the type having printing plate cylinders and impression cylinders, in which each printing plate cylinder is in continuous contact with a compression cylinder during printing operations, and in which the continuous contact between the printing and impression cylinders provides friction feeding means continuously feeding the web through the press; means insuring constant tension on the web during the printing operation comprising a printing plate cylinder of a very slightly increased diameter for the last impression of the press.
